UNITED STATES PATENT OFFICE

2,686,680

RAM OPERATING MECHANISM FOR
COMPOSING MACHINES

Merritt G. Stewart and Chester A. Macomic,
Chicago, Ill., assignors, by direct and mesne
assignments, to Patent Development Corpora-
tion, Chicago, Ill., a corporation of Illinois

Application October 29, 1949, Serial No. 124,394

20 Claims. (Cl. 276—9)

1

Our invention relates to improvements in a ram operating mechanism for composing machines and the like, and has for one object to provide a ram operating mechanism operated under the control of a typewriter carriage for driving the ram which forces together a plurality of character carrying strips, which have been previously loosely assembled by assembling and selecting means controlled by the typewriter, but not forming a part of the present invention.

Another object of the invention is to provide means for adjusting the movement of the ram automatically in consonance with the width of each of the character strips and in consonance with the number of character strips assembled in a line.

It will be understood that the character strips which are to be assembled to form a pattern or a line of characters, carry characters of varying widths and therefore the strips are tapered. They will be longitudinally displaced by means illustrated in co-pending application Serial No. 58,003 filed November 2, 1948, to form a line of selected characters.

As the strips are longitudinally adjusted to bring these characters of varying widths into alignment, the over-all width occupied by any given number of strips varies as a result of the variation in width of the characters in the line. Assuming a line of standard length, all the letters are wide, a much smaller number of letters can be put in the line than if they are all narrow and the number of strips which may be assembled to form a line of given length will vary in consonance with variation in the proportion of wide and narrow characters. It will be understood, of course, that only enough strips are assembled in the line to fill the line.

The purpose of the ram control is to insure that the ram will bring the strips together in proper spacing and to insure that the ram will move exactly the right distance to force together the particular number and width of strips on which it works in the composition of a single line.

The ram must be positively driven because the character strips must all be squeezed together with the same compression so that the selecting mechanism when it makes its selection will accurately control not only the width of the line but the appearance of the line. Therefore, the movement of the ram must be controlled with maximum accuracy.

Other objects will appear from time to time throughout the course of the specification and claims.

2

Our invention is illustrated more or less dia-
grammatically in the accompanying drawings,
wherein:

5 Figure 1 is a vertical section through our appa-
ratus with parts omitted but illustrating the
typewriter and the ram control;

Figure 2 is a section along the line 2—2 of
Figure 1;

10 Figure 3 is a section along the line 3—3 of
Figure 1;

Figure 4 is a view looking in the direction of
the arrows 4—4 of Figure 1;

Figure 5 is a section along the line 5—5 of
15 Figure 4;

Figure 6 is an enlarged section of the right-
hand portion of Figure 1;

Figure 7 is a section along the line 7—7 of
20 Figure 6;

Figure 8 is a side elevation, in part section
with parts omitted, of Figure 4;

Figure 9 is a section along the line 9—9 of
25 Figure 6.

Figure 10 is a side elevation of the driving
means for the ram control with parts broken
away; and

Figure 11 is a section along the line 11—11 of
20 Figure 10.

Like parts are indicated by like characters
throughout the specification and drawings.

30 1, 2 and 3 indicate cross members of the main
frame of our composing machine. That frame
is not generally illustrated because to do so
would obscure those elements which form a par-
ticular part of our invention with respect to
35 which the present application concerns itself.
Suffice it to say that the frame members 1, 2
and 3 are tied together by any suitable longi-
tudinal framework and are adapted to be sup-
ported thereby on the ground or any other suit-
able base.

4 is a typewriter having a keyboard and other
usual typewriter equipment. 5 is a rack adapted
to be longitudinally displaced as a result of and
in coordination with the movement of the type-
writer carriage. That rack is in mesh with a
45 gear 6 on a shaft 7 in bearings 8 and 9, the bearing
8 being associated with that part of the struc-
ture which supports the typewriter, the bearing
9 being associated with that part of the struc-
ture which supports the ram. The shaft 7 car-
ries adjacent the bearing 9 a gear 10 in mesh
50 with a rack 11, the purpose of which will herein-
after appear.

55 A bracket 12 carried on the frame member 1
beneath the typewriter 4 carries a pivot pin 13

on which is rotatably mounted a lever 14. 15 is a handle pivoted on the lever 14 at the fulcrum 13, the handle being held against rotation with respect to the lever about the pivot or fulcrum 13 but free to move vertically. The handle 15 is tied to one end of the lever 14 by a pin 16 and spring 17 which yieldingly forces the V-block 18 into engagement with one of the notches 19 on the yoke 20 which is carried on the frame 21 which supports the typewriter 4. The purpose of this handle is so that the operator may set, as will hereinafter appear, the position of the mechanism to insure that the movement of the ram will correspond to the desired length of line.

22 is the ram frame carried by the frame members 2, 3, 23, 24 are ram tracks on the ram frame 22 and 25 is the ram mounted for reciprocation between the tracks 23, 24 and having a contact head 26 adapted to engage one side of an assembly of character strips 27 which are longitudinally movable, to compress them against an abutment 28. 29 is a web extending downwardly from the ram 25 below the tracks 23, 24. It carries a link 30 pivoted on the ram lever 31, which lever is pivoted at 32 on the ram frame 22.

33 is the ram actuating carriage. It reciprocates in sliding bearings 34, 35 on the ram frame 22. Fixed lever 36 rigidly held on the carriage 33 carries a roller 37 engaging a groove 38 in the cylindrical cam 39. The cam 39 is fixed on the shaft 40 so that as the cam shaft 40 rotates, carriage 33 is caused to reciprocate.

Extending upwardly from the carriage 33 is a pivot plate 41 on which is pivotally mounted a drive adapted to travel in a curved slot 44 on a drive block 45 on the lever 31 so that when the lever carriage 33 reciprocates, the lever 42 in the slot 44 causes rotation of the lever 31 and up and down movement of the roller 43 can change the radius through which the power of the lever 42 is applied to the ram lever 31 about the axis of the pivot 32.

The angular position of the drive lever 42 is controlled by a slide 45. This slide reciprocates in bearings 46, 47, is held in an upper position by a spring 48 and carries a channel member 49 in which rides a roller 50 on the end of the lever 42 furthest from the lever 31 so that if the slide 45 is moved up and down, it causes a rotation of the lever 42 and movement of the roller along the slot 44. The channel 49 is parallel with the line of movement of the lever carriage so that the lever carriage and adjustment lever 42 are free to move in a direction perpendicular to the axis of rotation of the lever 31 without change in angular position of the lever 42.

51 is an angle plate on the slide 45. It is opposed to an angle plate 52 mounted on the sliding lock member 53, which member is free to move in a direction at right angles to the direction of movement of the slide 45 and is urged to the right by the spring 54, so that when the slide 45 moves down the angle member 51 moves down with it and this permits the member 52 to move to the right thus locking the slide 45 against upper movement. This lock is released by a latch member 55 on the lever 31 adjusted by means of the screw 56 and urged to the downward position by means of the spring 57. As the lever 31 rotates in a clockwise direction, the latch member 55 snaps down past the end of the slide 53, and then when the lever comes back it forces the member 52 to the left thus permitting upward travel of the slide 45 under the urge of the spring 48.

As the typewriter carriage moves toward the right, rotating the shaft 7 to drive the rack 11, the carriage 60 which carries the rack 11 travels along the track 61 carrying with it the pivot pin 62 which travels in the slot 63 on the lever 64. Thus as the line is written on the typewriter, the pivot pin 62 for the lever 64 moves to the left in Figure 4. Thus there is a direct relationship between the position of the pivot of the lever 64 and the position reached by the typewriter carriage.

66 is a drive bar slotted at 67 and traveling on pins 68 for lengthwise reciprocation. This drive bar is connected by a screw adjusted stirrup 69 with the end of the lever 64. When this bar moves upwardly, the pivot pin 62 having been previously moved to the left away from the starting position in Figure 4, the lever 64 moves downwardly to depress the slide 45, rock the lever 42 and increase the effective radius through which the thrust of the lever 42 is applied to the lever 31 when the ram lever carriage is reciprocated.

70 is a spring housing, 71 a tension tape extending from that spring housing to the carriage 72 associated with the pin 62. It is to be understood that the pin 62 is, by the movement of the rack 11, forced to the left against the tension of the spring 71 but is free to move to the right when the carriage of the typewriter causes movement of the rack 11 in the opposite direction. But there is no positive connection between these parts so that the carriage which actuates the pin 62 may be withdrawn, leaving the pin in its adjusted position.

35 As the carriage 72 and pivot pin 62 move toward the left and approach the position they are to occupy at the end of a line, the magnet 73 on the carriage 60 approaches the mercoind switch 74 and closes a circuit through the solenoid 75. 40 This causes the solenoid plunger 76 working through the link 77 on the bell crank lever 78 to rotate the bell crank lever in a counter-clockwise direction, causing the toe 79 of the bell crank lever to engage the pin 62 and move it forwardly 45 to the end of its desired excursion as set by the operator by manipulation of the handle 15. 80 is an adjusting screw to accurately set this position. 81 is an adjusting screw abutment for the lever 64. 82 is a contact button on the lever 64 which 50 engages the slide 45.

With reference to Figure 6, note that the lever 64 is made in two parts and slotted to accommodate the sliding block 72 and its pin 62. The lever 64 is supported by the pin 62 which extends through slots in supporting members 83, 84 positioned at either side of the lever which are secured to the frame member 22. The carriage 60 is provided with a lug 85 having an abutment button 86 adapted to engage the pin 62.

60 Once the switch 74 has closed the circuit to cause the toe of the bell crank lever 78 to hold the pivot 62 in place, the typewriter carriage may be withdrawn and the operator may resume writing while the machine goes on with its work. 65 As soon as the magnet 73 moves back away from the switch 74, the pin 62 remaining in place, the circuit is open when the spring 93 rotates the bell crank lever latch 78 into the inoperative position. At that time, however, there is enough pressure on the system so that the pivot remains in place by friction for a sufficient length of time to permit the apparatus to complete its cycling. The operator is free to go on writing with the typewriter and moving the carriage 60 back 70 toward the lefthand position, but normally, by 75

the time she has written a few letters or words, release will have taken place and the pivot pin 62 on the carriage 72 will go back to the right far enough to meet the abutment 86 on the carriage 60.

With reference to Figure 4, the abutment button 86 on the carriage 60 moves the pivot pin 62 toward the right, whereas the spring 71 returns the pivot pin and associated carriage 72 to the left until it engages the abutment 86.

The solenoid 75, bell crank lever 78, switch 74 and adjusting screw 80 are mounted on a support 87 which is slidably mounted on guiding bars 88 supported by brackets 89 on the frame 22. Secured to the support 87 is a bar 90 carrying a roller 91 adapted to engage the forked member 92 carried by the lever 14.

Actuating means for the drive bar 66 are illustrated in Figures 10 and 11. The drive bar is provided at its lower end with an aperture 94 adapted to receive the pin or roller 95 on the lever 96. The lever is mounted on a shaft 97 carried by bearings 98 on the main frame 99. Secured to the shaft is a second lever 100 having a cam plate 101 at its free end. In alignment therewith is a roller 102 on a lever 103 which is pivoted as at 104 to a pair of ears 105 on one end of a bell crank lever 106. The lever 106 is pivoted as at 107 on the frame 99 and is secured to a pull bar actuating lever 108 for the character strips 27, the details of which are not illustrated since they form no part of the present invention.

109 is a spring secured at one end to a pin 110 on the bell crank lever 106 and the other end to a pin 111 on the lever 103. In one position, illustrated in full lines in Figure 11, the spring retains the roller 102 on the lever 103 in alignment with the cam plate 101. As the pull bar actuating lever is rotated by suitable means counter-clockwise to the dotted line position, the roller 102 engages the cam plate 101 and rotates the levers 100 and 96 counter-clockwise to the dotted line position, thus moving the drive bar 66 upwardly to actuate the lever 64. Near the end of rotation of the bell crank lever 106, an adjustable contact 112 on a lug 113 integral with the lever 103 engages a cam 114 on the frame 99 and rotates said lever to the position indicated in dotted lines in Figure 11, thus moving the roller 102 out of alignment with the cam plate 101 on the lever 100. The spring 109 is thereby moved past the center of the pivot pin 104 and retains the lever in the dotted line position until, at the return movement of the bell crank 106, an adjustable contact 115 on a downward projection 116 on the lever 103 engages a cam 117 on the frame 99 and returns the lever 103 to initial or full line position. It will be understood that during the return movement of the bell crank, the roller 102 remains out of alignment with the cam plate 101 until it has reached a position below said cam plate.

Although we have shown an operative form of our invention, it will be recognized that many changes in the form, shape and arrangement of parts can be made without departing from the spirit of our invention, and our showing is therefore to be taken as, in a sense, diagrammatic.

We claim:

1. In a composing machine, a ram, a ram lever adapted to reciprocate the ram, drive means for the lever comprising a driving lever movable toward and from the ram lever and means for rocking the driving lever to vary the distance

between the point of engagement between the driving lever and the ram lever and the fulcrum of the ram lever.

2. Driving means for the ram of a composing machine including a ram lever, fulcrumed at one end, a link connection between the other end of the lever and the ram, a ram lever actuating carriage, means for moving it along a path at right angles to the axis of rotation of the ram

10 lever, a drive lever pivoted on the carriage, a guide on the ram lever concentric with the fulcrum of the drive lever, a driving connection between the drive lever and the guide on the ram lever, means for rotating the drive lever to vary the point of contact between the drive lever and the ram lever whereby the distance between the fulcrum of the ram lever and the point of application of the force of the driving lever may be adjusted.

3. In a composing machine, a plurality of longitudinally movable character bars arranged side by side, a fixed abutment at one side of the group of character bars, a ram adapted to engage the other side of the group in opposition to the fixed abutment and compress the bars side by side against the abutment, means for moving the ram toward and from the abutment, a typewriter having a carriage and means controlled by the typewriter carriage for varying the excursion of the ram.

4. In a composing machine, a longitudinally movable ram, a ram lever pivoted at one end, a connection between the other end of the ram lever and the ram, means for rotating the ram lever, a drive member and means for moving it in a path at right angles to the axis of the lever, a driving lever interposed between the drive member and the ram lever, and means for adjusting the angular position of the driving lever to change the distance between the fulcrum of the ram lever and the point of application of the force rotating the ram lever.

5. In a composing machine a ram, a ram lever adapted to reciprocate it, means for rocking the ram lever including a carriage movable along a path perpendicular to the axis of rotation of the ram lever, generally parallel with the line of travel of the ram, a driving connection between the carriage and the ram lever including a driving lever pivoted on the carriage, a thrust connection between one end of the driving lever and the ram lever and means for adjustably rotating the driving lever to displace the point of thrust between the ram lever and the drive lever to vary the angular movement of the drive lever in response to unit movement of the carriage.

6. In a composing machine a ram, a ram lever adapted to reciprocate it, means for rocking the ram lever including a carriage means for constraining it to movement along a path perpendicular to the axis of rotation of the lever, generally parallel with the line of travel of the ram, yielding means for locking the ram lever in the position reached by it at the end of its driving stroke.

7. In a composing machine a ram, a ram lever adapted to reciprocate it, means for rocking the ram lever including a carriage movable along a path perpendicular to the axis of rotation of the ram lever, generally parallel with the line of travel of the ram, a driving connection between the carriage and the ram lever including a driving lever pivoted on the carriage, a thrust connection between one end of the driving lever and the ram lever and means for adjustably rotating

the driving lever to displace the point of thrust between the ram lever and the drive lever to vary the angular movement of the drive lever in response to unit movement of the carriage, yielding means for locking the drive lever in the position reached by it at the end of its driving stroke.

8. In a composing machine including a typewriter, a plurality of movable character bars and means controlled by the typewriter for positioning the bars to assemble a line of characters, one character on each bar, a fixed abutment at one end of the line, a ram movable toward and from the group of bars at the other end of the line in opposition to the abutment, a ram lever, a fixed pivot for one end of the lever, a connection between the other end of the lever and the ram, and means for rotating the ram lever through an angle varying as the length of the line selected by the typewriter varies means for actuating the ram and controlling its excursion including a movable member, a driving lever interposed between the driving lever and the ram and means for moving the point of contact between the driving lever and the ram lever toward and from the ram lever pivot.

9. In a composing machine including a typewriter, a plurality of movable character bars and means controlled by the typewriter for positioning a plurality of the character bars to form a line of characters, one character on each bar, means for squeezing together the assembled bars, including an abutment and a ram in opposition to one another, with the bars between them, and means for forcing the ram toward the abutment against the type bar through an excursion the length of which is controlled by the typewriter.

10. In a composing machine including a typewriter, a plurality of movable character bars and means controlled by the typewriter for positioning a plurality of the character bars to form a line of characters, one character on each bar, means for squeezing together the assembled bars, including an abutment and a ram in opposition to one another, with the bars between them, and means for forcing the ram toward the abutment against the type bar through an excursion the length of which is controlled by the typewriter in consonance with the length of such line when it is less than a pre-determined length.

11. In a composing machine including a typewriter, a plurality of movable character bars and means controlled by the typewriter for positioning a plurality of the character bars to form a line of characters, one character on each bar, an abutment and a ram in opposition to one another, with the bars between them, and means for forcing the ram toward the abutment to assemble and compress the character bars in a line of predetermined length and means controlled by the typewriter for causing the ram to squeeze the assembled bars together when the line is less than the predetermined length.

12. In a composing machine, means for longitudinally displacing a plurality of elongated character bars to form a line of characters, means for applying pressure to the bars in a direction perpendicular to their length to squeeze them together, said means including a ram movable toward and from the bars, and means for pre-adjusting the excursion of the ram before the pressure is applied.

13. In a composing machine, means for positioning a plurality of movable character bars to assemble a line of characters, one character on each bar, means for applying lateral pressure

to the type bars to squeeze the bars together, said means including a ram movable along a path in general alignment with the line of characters and means for pre-limiting the excursion of the ram whereby the pressure applied to the bars by the ram is independent of the length of the line, the pre-limiting means including a carriage, a driving connection between it and the ram and means responsive to the number of characters selected for changing the position of the driving connection.

14. In a composing machine, means for positioning a plurality of movable character bars to assemble a line of characters of pre-determined length, one character on each bar, means operative when the number of bars so assembled is not sufficient to complete the pre-determined length of line, for applying lateral pressure to the type bars to squeeze the bars together, said means including a ram movable along a path in general alignment with the line of characters and means for pre-limiting the excursion of the ram whereby the pressure applied to the bars by the ram is independent of the length of the line, the pre-limiting means including a carriage, a driving connection between it and the ram and means responsive to the number of characters selected for changing the position of the driving connection.

15. In a composing machine, including means for selecting a plurality of movable character bars to form a line of characters, one character on each bar, means for displacing said bars along a path in general parallelism with the line of characters to assemble a line of pre-determined length, said means including a ram movable toward and from the type bars and means for controlling the excursion of the ram to cause it to apply pressure to the bars after the assembly of the line when the number of bars so assembled is not sufficient to complete the pre-determined length of line, means for controlling the excursion of the ram including a lever, a connection between it and the ram, a carriage, a driving connection between it and the lever, means for displacing the carriage toward and from the lever and means for varying the point of contact of the driving connection with the lever toward and from the pivot of the lever.

16. In a composing machine, including means for selecting a plurality of movable character bars to form a line of characters, one character on each bar, means for displacing said bars along a path in general parallelism with the line of characters to assemble a line of pre-determined length, said means including a ram movable toward and from the type bars and means for controlling the excursion of the ram to cause it to apply pressure to the bars after the assembly of the line when the number of bars so assembled is not sufficient to complete the pre-determined length of line, and means for pre-limiting such additional excursion of the ram whereby the pressure applied to the bars by the ram is independent of the length of the line, the pre-limiting means including a carriage, a driving connection between it and the ram and means responsive to the number of characters selected for changing the position of the driving connection.

17. In a composing machine including a typewriter, a plurality of movable character bars and means controlled by the typewriter for positioning the bars to assemble a line of characters, one character on each bar, a fixed abutment at one end of the line, a ram movable toward and from

the group of bars at the other end of the line in opposition to the abutment, a ram lever, a fixed pivot for one end of the ram lever, a connection between the other end of the ram lever and the ram, and means including a driving member connected to the ram lever and means controlled by the typewriter for varying the distance between the fulcrum of the ram lever and the point of connection between the driving means and the ram lever.

18. In a composing machine including a typewriter, a plurality of movable character bars and means controlled by the typewriter for positioning a plurality of the character bars to form a line of characters, one character on each bar, means for squeezing together the assembled bars, including an abutment and a ram in opposition to one another, with the bars between them, and means for moving the ram toward the abutment through an excursion the length of which is controlled by the typewriter in consonance with the length of such line when it is less than a predetermined length, means controlled by the operator independent of the typewriter for controlling the length of line which can be selected by the typewriter, means for actuating the ram and controlling its excursion including a movable member, a driving lever interposed between the driving lever and the ram and means for moving the point of contact between the driving lever and the ram lever toward and from the ram lever pivot.

19. In a composing machine including a typewriter, a plurality of movable character bars and means controlled by the typewriter for positioning a plurality of the character bars to form a line of characters, one character on each bar, an abutment and a ram in opposition to one another, with the bars between them, and means for moving the ram toward the abutment to assemble the character bars in a line of predetermined

length and means controlled by the typewriter for causing the ram to squeeze the assembled bars together when the line is less than the predetermined length, means controlled by the operator independent of the typewriter for controlling the length of line which can be selected by the typewriter, means for actuating the ram and controlling its excursion including a movable member, a driving lever interposed between the

5 driving lever and the ram and means for moving the point of contact between the driving lever and the ram lever toward and from the ram lever pivot.

10 20. In a composing machine, including means for selecting a plurality of movable character bars to form a line of characters, one character on each bar, means for displacing said bars along a path in general parallelism with the line of characters to assemble a line of pre-determined length, said means including a ram movable toward and from the type bars and means for controlling the excursion of the ram to cause it to apply pressure to the bars after the assembly of the line when the number of bars so assembled

25 is not sufficient to complete the pre-determined length of line, means independent of the bar selecting means for establishing the length of line which can be selected.
